UNITED STATES PATENT OFFICE.

OSCAR W. JOHNSON, OF ROCKFORD, ILLINOIS, ASSIGNOR TO WARD-LOVE PUMP CORPORATION, OF ROCKFORD, ILLINOIS, A CORPORATION OF ILLINOIS.

WATER SOFTENER.

Application filed October 15, 1926. Serial No. 141,688.

This invention relates to water softeners and is principally concerned with improvements in the application in water softeners of the water distributing diaphragm of filter cloth disclosed in patent to Orland Russell Sweeney, No. 1,557,117, issued October 13, 1925.

The principal object of my invention is to provide for greater adaptability of the diaphragm to the requirements of larger water softeners and enable making whatever minor variations in construction become desirable in the application of the diaphragm to different sized units. For example, I provide, in place of a single piece of filter cloth supported between or on grids as disclosed in the Sweeney patent, a wall constituting the principal supporting and retaining means for the bed of zeolite material, provided with openings uniformly distributed throughout the cross section of the bed, each equipped with a separate piece of diaphragm material secured in such a way as to permit individual removal and replacement. Accordingly, no limitation within reasonable limits is imposed by this construction on the size of the unit in which the same may be used. Furthermore, the construction enables the simple removal and replacement of any separate pieces as compared with the difficulty in the other construction, as well as the expense thereby incurred, in having to remove and replace the entire diaphragm, when only a part thereof became unfit for further use.

A further feature of the present invention worthy of note is that the present construction enables the separate pieces to have freedom to buckle and flutter in the operation of the softener, which freedom was not permitted where the one-piece diaphragm had to be mounted in a special way because of its size. This materially diminishes the tendency for the diaphragm to become clogged. Obviously, by virtue of the present construction, the clogging of any separate pieces of diaphragm is easily remedied by the replacement of such pieces and any defective piece may be likewise replaced.

The invention is illustrated in the accompanying drawings wherein—

Figure 1 is a vertical section through the lower portion of a water softener tank equipped with a diaphragm of an improved design in accordance with my invention,

Fig. 2 is a horizontal section showing the diaphragm in plan;

Fig. 3 is an enlarged plan view of one of the separate diaphragm sections;

Fig. 4 is a section through Fig. 3; and

Fig. 5 is a section corresponding to Fig. 4 of a modified or alternative construction. Throughout the views, the same or similar reference numerals are applied to corresponding parts.

Referring for the present more particularly to Figs. 1 to 4, the invention is shown applied to a water softener tank 10 having a basin-shaped bottom 11 with which a lower pipe connection 12 communicates through a lead-in pipe 13 and elbow 14, as described in my Patent 1,628,541, issued May 10, 1927.

A bed of zeolite or other base-exchange water softening material is arranged to be supported within the tank 10 on the diaphragm, indicated generally by the reference numeral 15.

The latter, according to my invention, is provided of a special construction embodying, in effect, a network or patchwork of pieces 16 of filter cloth to remedy difficulties encountered in practice with a diaphragm composed merely of a single piece of filter cloth or equivalent material supported on or

between and reinforced by grids, as disclosed in the Sweeney patent above referred to. As described in said patent, the filter cloth diaphragm replaces a bed of sand or gravel by serving the purpose of uniformly distributing the flow of water through the bed of zeolite material supported thereon and also serving to filter the water and to retain the zeolite material with the water flowing in either direction. This filter cloth is preferably made from Monel metal so as to be non-corrosive and is so finely fabricated

that it appears opaque although the interstices between the woven strands permit the

water to pass through.

It is an object of my invention to provide a water softener having a diaphragm of the character described which is particularly adapted for use in large tanks.

free passage of water therethrough. In addition to being closely woven, the cloth is rolled so as to have the strands flattened and congested and thereby further to reduce the size 5 and shape of the interstices. Due to its construction, the cloth not only filters suspended matter from the water passing therethrough but distributes the water uniformly there across and, of course, retains the zeolite material. Needless to state, this material is rather costly and it, therefore, becomes a matter of considerable expense if the entire diaphragm has to be replaced. Prior to my present invention, a defect of any consequence, even if only in a single spot on the diaphragm, made it necessary to remove and replace the entire diaphragm at great trouble and expense. Furthermore, especially in the case of larger sized tanks, where the span 10 of filter cloth was comparatively great, specially designed grids had to be provided to support or properly reenforce the diaphragm. These grids, besides forming a rather appreciable obstruction to the flow of water, frequently resulted in electrolytic action with 15 the diaphragm and consequent disintegration. There was also some evidences of clogging, especially where the diaphragm was held taut and had no freedom to buckle or 20 weave back and forth with the sudden surges of water flow therethrough or the reversals of flow. In accordance with my invention, as will presently appear, it is possible to support and secure the individual pieces of filter 25 cloth 16 in such a way that a certain amount of buckling or fluttering will occur. This greatly reduces the tendency for the filter cloth to clog, as any lodged particles will tend to work out. Furthermore, if any particular piece should prove to be unfit for further use after a time, it is a simple matter to 30 replace the same and the same is true if any piece shows evidences of being defective. It is obviously a matter of hardly any consequence in expense to replace individual 35 pieces as compared with replacement of an entire diaphragm of large dimensions.

The diaphragm 15 comprises a plate 17 supported in any suitable manner above the bottom 50 11 so as to serve as a supporting and retaining wall for the zeolite material. The plate 17 has a plurality of openings 18 provided therein substantially uniformly distributed throughout the cross-section of the bed 55 of zeolite material. The pieces of filter cloth 16 span the openings 18 and are suitably clamped in position by rings 19 and bolts 20. The marginal edges of the filter cloth pieces 16 have rings of gasket material 21 thereon so as to insure against leakage 60 between the plate 17 and the filter cloth pieces 16. I prefer to provide the gaskets 21 of vulcanized rubber so that the filter cloth pieces are each insulted with respect to the plate 17 65 and there is no possibility of electrolytic ac-

tion therebetween. The gaskets, while serving to hold the filter cloth pieces relatively securely, nevertheless permit of a buckling or fluttering of the filter cloth with the surges of water flow therethrough or upon a reversal of flow, as in the case of regeneration of the water softener. This action of the filter cloth tends to work out any particles which may lodge in the interstices of the cloth so that the tendency for clogging is very greatly reduced. In Fig. 4, it will be noted that the openings 18 are appreciably smaller in diameter than the exposed area of the filter cloth pieces 16. The advantage thereby derived is that the plate 17 is not weakened any more than is absolutely necessary and still the aggregate exposed area of filter cloth is relatively large in proportion to the entire area of the plate 17.

The operation of the present diaphragm is substantially the same as that secured with a single piece diaphragm as shown in the Sweeney patent; that is, as regards the distribution of the water flow uniformly throughout the cross section of the bed and the filtering of the water before its passage upwardly through the zeolite material. In the present case, however, the separate pieces 16 are free to buckle upwardly and to flutter somewhat in the normal operation of the softener when the flow is upward. When the softener is regenerated and the flow is downward, the collected matter on the under side of the filter cloth pieces is washed off and any particles which may have become lodged in the interstices of the cloth will tend to become dislodged especially when the cloth buckles downwardly under the combined pressure of the zeolite material and the downwardly flowing brine. With the present construction there is obviously no limitation as to size of units in which the diaphragm may be installed. The plate 17 is simply designed to fit a stated sized tank and equipped with the proper number of openings 18. The filter cloth pieces 16 are then provided having a gauge coarser or finer, depending on the operating requirements of the unit, that is, the gauge may become coarser in larger sized units in proportion to the number of openings covered if the pressure is assumed to be the same for a larger or smaller sized unit. I have found that it is desirable to provide radial slots 26 in the underside of the rings 19 for the purpose of jetting water in the case 115 of upward flow operation outwardly for contact with the zeolite material between the pieces of diaphragm material. In other words, the provision avoids the likelihood of dead spaces which the incoming water would 120 not traverse and tends toward a definite uniform distribution of water flow through the bed of zeolite material. The provision is, furthermore, of advantage after regeneration during the flushing operation. During regen- 125 130

- eration, when the flow is downward, there is obviously a tendency for the material to pack over the separate pieces of diaphragm material and in between these pieces on top of 5 the plate 17. During the flushing operation, jets of water sent through the slots 26 serve to break up the packed material and thoroughly rinse out the brine and the entire bed is properly agitated. The slots 26, on the 10 other hand, are not sufficiently wide to seriously affect the holding of the diaphragm pieces by their gaskets. The inspection plate, shown at 22 in Fig. 1, is provided to cover the man hole 23 which affords easy access to 15 the diaphragm 15 whenever an inspection and repair of the water softener is to be made.
- In Fig. 5, I have illustrated a slightly modified construction in which the filter cloth piece 16 is clamped in position by the ring 20 19' over a gasket ring 24, the ring 19' being provided with an annular groove 25 so that the filter cloth is crimped and thus positively held at its marginal edges. Obviously, the filter cloth pieces may be secured in this way 25 or in a variety of other ways with equal facility permitting of the individual removal and replacement of the pieces.

I claim:

1. In a water softener having a bed of base-exchange material, a perforated supporting and retaining wall for said material arranged to serve as a framework onto which may be fastened a network or patchwork of pieces of diaphragm material, a plurality of pieces of diaphragm material for said network or patchwork, and individual means for each piece of diaphragm material for securing the same to said wall in such a way as to permit its separate removal and replacement while 40 permitting each piece to buckle individually under the action of the water flowing therethrough, each of said pieces of diaphragm material being provided of substantially circular form with rings of gasket material on its marginal edges on opposed faces, and the means for securing the same in place comprising a ring arranged to be superposed on the piece of diaphragm material and to be fastened to the supporting and retaining wall 45 whereby to clamp the piece of diaphragm material in place between its rings of gasket material.
2. In a water softener having a bed of base-exchange material, a perforated supporting and retaining wall for said material arranged to serve as a framework onto which may be fastened a network or patchwork of pieces of diaphragm material, a plurality of pieces of diaphragm material for said network or patchwork, and individual means for each piece of diaphragm material for securing the same to said wall in such a way as to permit its separate removal and replacement while 55 permitting each piece to buckle individually under the action of the water flowing therethrough, each of said pieces of diaphragm material being provided of substantially circular form and of substantially larger diameter than the openings in the supporting and retaining wall, and also having rings of gasket material on its marginal edges, the inside diameter of which is likewise substantially larger than the opening in said wall, the gasket material serving to space the diaphragm material from said wall 60 and the opening therein, and the said means for securing the latter in place comprising a ring arranged to be superposed thereon and to be fastened to the supporting and retaining wall so as to clamp the diaphragm material.
3. In a water softener having a bed of base-exchange material, a perforated supporting and retaining wall for said material arranged to serve as a framework onto which may be fastened a network or patchwork of pieces of diaphragm material, a plurality of pieces of diaphragm material for said network or patchwork, and individual means for each piece of diaphragm material for securing the same to said wall in such a way as to permit its separate removal and replacement while 65 permitting each piece to buckle individually under the action of the water flowing therethrough, each of said pieces of diaphragm material being provided of substantially circular form with rings of gasket material on its marginal edges on opposed faces, and the means for securing the same in place comprising a ring arranged to be superposed on the piece of diaphragm material and to be fastened to the supporting and retaining wall whereby to clamp the piece of diaphragm material in place between its rings of gasket material.
4. In a water softener having a bed of base-exchange material, a perforated supporting and retaining wall for said material arranged to serve as a framework onto which may be fastened a network or patchwork of pieces of diaphragm material, a plurality of pieces of diaphragm material for said network or patchwork, and individual means for each piece of diaphragm material for securing the same to said wall in such a way as to permit its separate removal and replacement while 70 permitting each piece to buckle individually under the action of the water flowing therethrough, each of said pieces of diaphragm material being provided of substantially circular form and of substantially larger diameter than the openings in the supporting and retaining wall, and also having rings of gasket material on its marginal edges, the inside diameter of which is likewise substantially larger than the opening in said wall, the gasket material serving to space the diaphragm material from said wall and the opening therein, and the said means for securing the latter in place comprising a ring arranged to be superposed thereon and to be fastened to the supporting and retaining wall so as to clamp the diaphragm material.

in place between its rings of gasket material.
5. In a water softener having a bed of water softening material, a supporting and/or retaining wall having one or more openings therein, one or more pieces of diaphragm material for said openings, each preferably of circular form with rings of gasket material on its marginal edges on opposed faces, and

one or more ring-shaped elements for securing said pieces to the wall covering the openings fastened to the wall in such a way that the diaphragm material is clamped in place between its rings of gasket material. 10

In witness of the foregoing I affix my signature.

OSCAR W. JOHNSON.
